COMBINED PROPULSION AND STEERING UNIT FOR A BOAT OR THE LIKE

Nils Hansson, Goteborg, Sweden, assignor to AB Penta,
Goteborg, Sweden

Filed June 28, 1960, Ser. No. 61,137

Term of patent 14 years

(Cl. D71—1)

FIG. 1 is a perspective view of a combined propulsion and steering unit for a boat or the like showing my new design and showing the front and one side thereof;

FIG. 2 is a front elevational view thereof; and

FIG. 3 is a top plan view thereof.

The fragment of flexible cable tubing shown in FIG. 1 is for illustrative purposes only.

I claim:

The ornamental design for a combined propulsion and steering unit for a boat or the like, as shown.
